(57) **CLAIM**

The ornamental design for an air sleeping pad, as shown and described.

DESCRIPTION

FIG. 1 is a first perspective view of an air sleeping pad showing my design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The dashed or broken lines shown in the drawings depict portions of the air sleeping pad in which the design is embodied that form no part of the claimed design.
